(57) **CLAIM**

We claim the ornamental design for a security tag holder, as shown and described.

DESCRIPTION

FIG. 1 is a perspective illustration of a security tag holder mounted to a cylindrical object;

FIG. 2 is a rear perspective illustration of the security tag holder of FIG. 1;

FIG. 3 is a front view of the security tag holder of FIG. 1; FIG. 4 is a rear view of the security tag holder of FIG. 1; FIG. 5 is a first side view of the security tag holder of FIG. 1;

FIG. 6 is a second side view, opposite the first side view, of the security tag holder of FIG. 1;

FIG. 7 is a top view of the security tag holder of FIG. 1; and, FIG. 8 is a bottom view of the security tag holder of FIG. 1. The broken lines form no part of the claimed design.
